[57] CLAIM

The ornamental design for a candle holder, as shown and described.

DESCRIPTION

FIG. 1 is a perspective view of a candle holder showing
my new design;

FIG. 2 is a top plan view thereof;

FIG. 3 is a bottom plan view thereof;

FIG. 4 is a front elevational view thereof, the rear being a mirror image of the same; and,

FIG. 5 is a side elevational view thereof, the opposite side being a mirror image of the same.
